UNITED STATES PATENT OFFICE.

STEVE BABIC, OF HOMESTEAD, PENNSYLVANIA.

BOTTLE-STOPPER.

No. 834,038.

Specification of Letters Patent.

Patented Oct. 23, 1906.

Application filed June 14, 1906. Serial No. 321,768.

To all whom it may concern:

Be it known that I, STEVE BABIC, a resident of Homestead, in the county of Allegheny and State of Pennsylvania, have invented a new and useful Improvement in 5 Bottle-Stoppers; and I do hereby declare the following to be a full, clear, and exact description thereof.

My invention relates to non-refillable bottles, its object being to provide a device of this character which is simple in construction and from which the contents may be readily poured, but which it is impossible to refill after the contents have once been discharged 15 therefrom.

My invention consists, generally stated, in providing in the neck of the bottle an enlarged cavity with a seat adapted to receive a ball which closes the opening leading into the bottle when the bottle is in a normal position and which is adapted to roll from said seat when the bottle is turned for pouring, together with a split ring inserted within the bottle-neck above said enlarged cavity, so as 25 to prevent the ball from escaping from the neck of the bottle.

I have illustrated my invention in connection with the accompanying drawings, in which—

30 Figure 1 is a vertical section through the neck of a bottle with my invention applied thereto, and Fig. 2 is a perspective view of the split ring removed.

Like numerals indicate like parts.

35 Referring to the drawings by numerals of reference, 2 is the body of the bottle, and 3 the neck. This neck is formed practically of three parts—namely, the enlarged portion 4, forming the cavity 5, the tapering portion 40 6, forming the tapered seat 7, and the stopper portion 8, adapted to receive the cork or other stopper.

Within the cavity 5 is the ball 9, which may be formed of any suitable material and 45 which ordinarily closes the opening 10, leading into the body of the bottle. The ball 9 is of sufficient weight, so that when the bottle is in a vertical or substantially vertical position the ball will be seated, as shown in

50 Fig. 1. Within the tapering seat 7 of the bottle-neck is the split ring 11, formed of

spring-steel of suitable resiliency, the upper end of said split ring bearing against the shoulder 12 and the lower end of said split ring being substantially flush with the shoulder 13. 55

In filling the bottle with the liquid contents the bottle is filled in the ordinary way and the ball 9 is then dropped down through the neck until it seats itself within the cavity 5. The split ring 11 is then inserted in the 60 neck of the bottle and is forced down until it passes beyond the shoulder 12, whereupon the said ring expands and fits up against the inner wall of the bottle-neck, so as to be securely held therein, while owing to its tapering form there is no liability of its slipping from its position. When the ring 11 is once in position, it is impossible to remove the same without breaking the bottle-neck, as after it has once sprung beneath the shoulder 70 12 it is practically impossible to reach it. When it is desired to pour the contents from the bottle, the bottle is turned to the proper angle, whereupon the ball 9 will roll from the opening 10, and as the cavity 5 is of sufficient 75 size to permit the ball to roll to one side without obstructing the passage through the neck of the bottle the contents will pass out through the split ring 11, through the upper portion 8 of the neck, and so be discharged. 80 If, however, an attempt is made to refill the bottle after its contents have been discharged it will be found that if the liquid is poured into the bottle the ball 9 will resume its seat, and so prevent the entrance of the liquid 85 into the body portion of the bottle. I thus provide a simple form of non-refillable bottle which is simple in construction, and yet which will effectually prevent an attempt to refill the bottle after its contents have once been 90 discharged therefrom.

What I claim is—

1. In a non-refillable bottle, the neck having an enlarged portion, a ball therein adapted to close the opening leading into the bottle and a split ring engaging the interior of the bottle-neck above said cavity, a shoulder formed in said bottle-neck the upper end of said ring engaging said shoulder formed in said bottle-neck. 95

2. In a non-refillable bottle, a bottle-neck having an enlarged cavity formed therein, a 100

ball within said cavity adapted to close the opening leading into the bottle, a tapering seat formed in said bottle-neck above said cavity and a split ring fitting in said tapering seat, a shoulder formed in said bottle-neck and the upper end of said ring engaging said shoulder formed in said bottle-neck.

In testimony whereof I, the said STEVE BABIC, have hereunto set my hand.

STEVE BABIC.
